UNITED STATES PATENT OFFICE.

JOHN B. BARNETT, OF PHILADELPHIA, PENNSYLVANIA, ASSIGNOR OF ONE-HALF
TO WILLIAM G. McCANN AND ONE-HALF TO ARTHUR E. SPELLISSY, BOTH OF
PHILADELPHIA, PENNSYLVANIA.

DISPLAY DEVICE.

Application filed March 30, 1925. Serial No. 19,406.

This invention relates to display devices and has special reference to an automatically operating device for displaying successively a series of signs.

5 One important object of the invention is to improve the general construction of devices of this description.

A second important object of the invention is to provide an improved device of this 10 description with novel means for supporting the displaying signs.

A third important object of the invention is to provide a novel circuit closer for such devices.

15 A fourth important object of the invention is to provide novel sign shifting means for such a device.

With the above and other objects in view as will be hereinafter apparent, the invention 20 consists in general of certain novel details of construction and combinations of parts hereinafter fully described, illustrated in the accompanying drawings and specifically claimed.

25 In the accompanying drawings like characters of reference indicate like parts in the several views, and:

Figure 1 is a plan view of the invention removed from its casing.

30 Figure 2 is a side elevation thereof.

Figure 3 is an end elevation taken from the right hand end of Figure 1.

Figure 4 is a section on the line 4-4 of Figure 1.

35 Figure 5 is a section similar to Figure 4, showing the contact closed.

Figure 6 is an enlarged detail view, substantially on the line 6-6 of Figure 2, showing the manner of supporting this end of 40 the device.

Figure 7 is a wiring diagram illustrating the electric connections of the device.

In the present embodiment of the invention there is provided a base 10. At one end 45 of this base there is mounted a standard 11 whereon is a socket 12 supporting an elongated lamp 13. Extending from the standard 11 is a frame 14 provided with a sleeve or collar 15 which not only supports the front end of the socket but also receives the base of the lamp 13. This sleeve has, at 50 its inner end a journal bearing whereon is mounted a disk 17 which is connected by rods 18 with a similar disk 19 provided with

a hub 20 having a groove 21 therein. These 55 disks and rods, when the signs are mounted thereon form a rotary screen. This hub 20 is supported by a forked standard 22 which fits in the groove 21. On the hub 20 is a ratchet 23 and adjacent the standard 22 is 60 a bracket 24 of inverted J-shape. Slidably mounted in this bracket is a bar 25 whereon is pivoted a pawl 26 engaging the ratchet 23 when reciprocated to rotate, the latter 65 being step by step movement. Also at this 65 end of the device is supported a bracket 27 whereon is mounted a magnet 28 having a pivot armature from which extends an arm 30 connected to the rod 25 so that each time the magnet is energized the rod is pulled in 70 one direction and each time the magnet is de-energized a spring 31 forces the rod back-wardly.

Thus, by alternate energization and de-energization of the magnet the rod 25 is 75 reciprocated and the frame formed by the disks 17 and 19 and bars 18 are intermittently rotated.

At the end of the device carrying the magnet there is provided a block 32 whereon is mounted spring bar 33 and a second spring bar 34 of expandable material, these two being united at the ends remote from the block 32 to a connector block and carrying a contact 35. From a suitable source of electric energy a wire or conductor 36 leads to the bar 33. The bar 34 is surrounded by a heating coil 37 one end of which is connected to the bar 33 while its other end is connected by a wire 38 to the other pole of 80 the source of energy. Under these conditions current flowing through the coil 37 will heat bar 34 and expand the same. This will cause movement of the contact 35, which is connected to the bar 33. Supported adjacent the contact 35 is a second contact 39 which is engaged by the contact 35 when the bar 34 is expanded. The contact 39 is 85 connected by a wire 40 with the magnet 28 and this magnet is in turn connected by 90 wire 41 with the wire 38. A lamp 42 is shunted off the wire 41 and grounded as at 43, the ground wire being indicated at 44. Under these circumstances the resistance 34 receives current and closes the contacts 35 and 39. This short circuits the current 95 through the magnet 28 and also through the lamp 42. Consequently the magnet 28 is 100 105

energized, the frame supporting the signs is rotated and the lamp is flashed.

However, as soon as this short circuiting takes place the coil 34 cools off and the short circuit is broken between the contact 35 and 39 thus de-energizing the magnet so that a pawl 26 slides back ready for a second step.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

In a device of the kind described, a base, a standard fixed to said base, a second standard fixed to said base in spaced relation to the first standard, a frame consisting of a pair of plates and rods connecting the same, a lamp socket carried by the second standard and having one portion thereof arranged to constitute a journal, one plate of said frame having an opening fitting said journal and

constituting a bearing for the frame, the first standard having an opening in its top and the second plate of the frame being provided with an extension constituting a journal for the frame and fitting the opening in the first standard, a ratchet wheel mounted on the last mentioned journal, a bracket of inverted J-shape having its longer leg fixed to the base, said bracket having its upper portion overhanging the ratchet and its terminal portion depending in parallel relation to the longer leg, a rod aligned above the ratchet and slidably mounted in the longer leg and terminal portion of the last mentioned bracket, a pawl pivoted to said rod and having one end depending therefrom to engage the ratchet and the remaining end extending over the rod to limit movement of the pawl in one direction, a second bracket mounted on the base in alignment with said ratchet, a magnet carried by the last mentioned bracket, an armature pivoted below said magnet, and an arm carried by said armature and connected to said rod whereby to move the rod upon energization of the magnet and thereby actuate the ratchet.

In testimony whereof I affix my signature

JOHN B. BARNETT.
